(57) **CLAIM**

The ornamental design for a medical injector, as shown and described.

DESCRIPTION

FIG. 1 is a perspective view of a medical injector in a compressed state having a spring clip disposed therewith in accordance with an embodiment of the present invention.

FIG. 2 is a top view of the medical injector of FIG. 1.

FIG. 3 is a left side view of the medical injector of FIG. 1.

FIG. 4 is a front view of the medical injector of FIG. 1.

FIG. 5 is a rear view of the medical injector of FIG. 1.

FIG. 6 is a right side view of the medical injector of FIG. 1.

FIG. 7 is a bottom view of the medical injector of FIG. 1.

FIG. 8 is a perspective view of the medical injector of FIG. 1 in an expanded state having the spring clip displaced therefrom.

FIG. 9 is a perspective view of the medical injector of FIG. 1 in an expanded state having the spring clip removed therefrom.

FIG. 10 is a top view of the medical injector of FIG. 1 in an expanded state having the spring clip removed therefrom.

FIG. 11 is a left side view of the medical injector of FIG. 1 in an expanded state having the spring clip removed therefrom.

FIG. 12 is a front view of the medical injector of FIG. 1 in an expanded state having the spring clip removed therefrom.

FIG. 13 is a rear view of the medical injector of FIG. 1 in an expanded state having the spring clip removed therefrom.

FIG. 14 is a right side view of the medical injector of FIG. 1 in an expanded state having the spring clip removed therefrom.

FIG. 15 is a bottom view of the medical injector of FIG. 1 in an expanded state having the spring clip removed therefrom.

FIG. 16 is a perspective view of the spring clip of FIG. 1 removed from the medical injector of FIG. 1.

FIG. 17 is a top view of the spring clip of FIG. 1 removed from the medical injector of FIG. 1.

FIG. 18 is a left side view of the spring clip of FIG. 1 removed from the medical injector of FIG. 1.

FIG. 19 is a front view of the spring clip of FIG. 1 removed from the medical injector of FIG. 1.

FIG. 20 is a rear view of the spring clip of FIG. 1 removed from the medical injector of FIG. 1.

FIG. 21 is a right side view of the spring clip of FIG. 1 removed from the medical injector of FIG. 1; and,

FIG. 22 is a bottom view of the spring clip of FIG. 1 removed from the medical injector of FIG. 1.
